UNITED STATES PATENT OFFICE

WILLIAM M. GRIFFIN AND CARROLL L. MERRIMAN, OF FORT WAYNE, INDIANA, AS-SIGNORS TO WAYNE COMPANY, OF FORT WAYNE, INDIANA, A CORPORATION OF INDIANA

DESIGN FOR A CASING FOR A LIQUID-DISPENSING APPARATUS

Application filed December 2, 1929. Serial No. 33,600. Term of patent 14 years.

To all whom it may concern:

Be it known that we, WILLIAM M. GRIFFIN and CARROLL L. MERRIMAN, citizens of the United States, residing at Fort Wayne, in the county of Allen and State of Indiana, have invented a new, original, and ornamental Design for a Casing for Liquid Dispensing Apparatus, of which the following is a specification, reference being had to the accompanying drawing, forming a part thereof.

The figure is a perspective view of a dispensing apparatus embodying our new design, it being understood that the opposite side of the apparatus is substantially the same as the side illustrated.

We claim:

The ornamental design for a casing for a liquid dispensing apparatus as shown and described.

WILLIAM M. GRIFFIN.
CARROLL L. MERRIMAN.
